UNITED STATES PATENT OFFICE.

JOSÉ GUARDIOLA, OF CHOCOLÁ, CENTRAL AMERICA.

IMPROVEMENT IN COFFEE-POLISHING MACHINES.

Specification forming part of Letters Patent No. 129,947, dated July 30, 1872.

Specification describing a new and Improved Coffee and Rice Hulling and Polishing Machine, invented by JOSÉ GUARDIOLA, of Chocolá, in the Republic of Guatemala, Central America.

Figure 1 represents a side elevation, partly in section, of my improved coffee and rice hulling and polishing machine. Fig. 2 is a top view of the same. Figs. 3, 4, and 5 are vertical sections of the polishing-stones.

Similar letters of reference indicate corresponding parts.

This invention has for its object to improve the polishing-faces of the rotary stones or articles between which coffee, rice, or other substances are placed to be polished or hulled.

In the drawing is represented the framework A of a mill, similar in construction to the mills for grinding grain. B B are the two polishing or hulling stones or blocks. Their acting surfaces I propose to improve by applying to them a covering, a, of India rubber, over which wire-cloth b is stretched, as shown in Fig. 3. The grain will be acted upon directly by the wire-cloth b, whose hard but rounded surfaces will suffice to remove the pellicles or polish the surfaces of the grains, but which will yield on the elastic cushion or support a sufficient to prevent all injury to the grains. Instead of being of rubber the cushion a may be of matting or other elastic material.

A stone or block thus prepared will be far

better for the purposes specified than the rigid surfaces heretofore employed in hulling and polishing machines. The chief difficulty to be overcome in hulling and polishing machines was to prevent the breaking of the grains while imparting the necessary degree of friction. By the aid of the cushioned wire surfaces this difficulty will be completely overcome.

It may in some cases only be necessary to have one of the blocks or stones prepared as above described, the other being a stone, as in Fig. 4, roughened or grooved at the polishing-surfaces, as usually.

The dark lines in Figs. 2 and 5 represent a thicker wire projecting a little over the wire-cloth b to form thereon lines of rounded projections diverging from the center to increase the roughness of the polishing-surfaces.

The improvement is applicable to the polishing-surfaces of all kinds of hulling or polishing machines.

Having thus described my invention, I claim as new and desire to secure by Letters Patent—

The wire-cloth b arranged on the cushion a of the stone or block B, substantially as and for the purpose specified.

J. GUARDIOLA.
